Patented Aug. 20, 1963

196,056

COIN-OPERATED AMUSEMENT DEVICE

Calvin N. Herzog, 58—15 205th St., Bayside, N.Y.

Filed Nov. 8, 1962, Ser. No. 72,430

Term of patent 14 years

(Cl. D34—5)

Fig. 1.

Fig. 2.

FIG. 1.

FIG. 2.

FIG. 3.

FIG. 4.

FIGURE 1 is a left side elevational view of a coin-operated amusement device, showing my new design;
FIGURE 2 is a top plan view thereof;
FIGURE 3 is a front elevational view thereof;
FIGURE 4 is a rear elevational view thereof;
FIGURE 5 is a section on the line 5—5 of FIGURE 1; and
FIGURE 6 is a section on the line 6—6 of FIGURE 1.
I claim:
The ornamental design for a coin-operated amusement device, as shown.
